United States Patent Office

Des. 181,638
Patented Dec. 10, 1957

181,638

MASKED HELMET

Jack F. Furrer, Wayland, and Abraham L. Lastnik, Framingham, Mass., and Marvin A. Jarvis, Midland, Mich., assignors to the United States of America as represented by the Secretary of the Army

Application March 29, 1957, Serial No. 45,508

Term of patent 14 years

(Cl. D3—13)

(Granted under Title 35, U. S. Code (1952), sec. 266)

Figure 1 is a side elevational view of a masked helmet embodying our new design, the mask being in the lowered position;

We claim:

The ornamental design for a masked helmet, substantially as shown.
